UNITED STATES PATENT OFFICE

HAROLD C. CLAUSEN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY BRAKING APPARATUS

Application filed January 14, 1932. Serial No. 586,556.

My invention relates to railway braking apparatus, and particularly to apparatus of the type comprising braking bars located in the trackway and movable into and out of position for engagement with the wheels of a car for the purpose of retarding the speed of the car.

More particularly my invention relates to apparatus of the type disclosed and claimed in an application for Letters Patent of the United States filed by Herbert L. Bone, on February 19, 1931, Serial No. 516,883, for railway braking apparatus. One object of my invention is the provision of means for improving certain features of the apparatus shown in the aforesaid Bone application.

I will describe three forms of apparatus embodying my invention, and will then point out the novel features thereof in claims.

In the accompanying drawings, Fig. 1 is a view showing one form of braking apparatus embodying my invention. Fig. 2 is a view showing a modification of the apparatus shown in Fig. 1 and also embodying my invention. Fig. 3 is a view showing another modification of the apparatus shown in Fig. 1 and likewise embodying my invention.

Similar reference characters refer to similar parts in each of the views.

Referring first to Fig. 1, the reference character R designates a track rail which is supported on a block H, and which block in turn is supported on a tie T. The block H carries two pivot pins B¹ and B² located beneath the track rail R and on opposite sides thereof. Pivotedly mounted on the pin B¹ is a lever L¹ having an arm 8 which extends to the side of the rail R opposite that on which the lever is pivoted. This arm carries a braking bar D¹ which extends parallel with the track rail R and which is adjustably attached to the arm by means of bolts 5 and a spacer F. A second lever L² is pivotedly mounted on the pin B² and has an arm which extends to the side of the rail opposite that on which this pivot pin is located, which arm supports another braking bar D² attached to the arm in the same manner as the bar D¹. The remaining arm of lever L² is pivotally connected at point 6 with a cylinder C, and the remain-

ing arm of lever L¹ is pivotally connected at point 7 with a piston E operating in the cylinder C. The cylinder C is provided with an inlet port 9 through which compressed air may at times be admitted to the upper end of the cylinder, thereby forcing the piston E downwardly in the cylinder and so spreading the right-hand arms of levers L¹ and L² apart.

The lever L² is provided with a lug 10 cooperating with a fixed stop G² on the tie T, and the lever L¹ is provided with a lug 11 cooperating with a fixed stop G¹ also fixed to the tie T.

The parts of the apparatus are so adjusted that lever L² is biased by gravity to swing in clockwise direction, whereas lever L¹ is biased by gravity to swing in counterclockwise direction. It follows that when cylinder C is disconnected from the source of fluid pressure, lever L² rests on stop G², whereas lever L¹ is swung to such position that piston E is at the upper end of cylinder C. The braking bars D¹ and D² are then both retracted from the track rail R, and so are out of engagement with a wheel W passing along this rail. When air is admitted to the upper end of cylinder C, however, lever L² will be swung in counter-clockwise direction and lever L¹ will be swung in clockwise direction, thereby moving both brake bars D¹ and D² toward the rail R into such positions that they will engage the two sides respectively of the wheel W. Lug 11 will then be in engagement with stop G¹, whereas lug 10 will be swung away from stop G².

It will be noted that bar D¹ swings around point B¹ as a center, so that when this bar is moved toward the wheel W it also moves upwardly a considerable distance above its normal position. Likewise, bar D² swings around pivot B² as a center, so that the same thing is true as to this bar. It follows that when the braking bars are in retracted positions, they are out of the path of any parts of the car or locomotive, whereas when they are moved into braking positions they become elevated so that they engage the wheel surfaces at points well above the tread of the wheel. It is well understood that in appa-

ratus of this kind it is desirable to move the braking bars downwardly at the same time they are moved away from the car wheels, and this object is accomplished by apparatus embodying my invention to a considerably greater degree than with the apparatus illustrated in the Bone application, referred to above.

Referring now to Fig. 2, the apparatus shown in this view is substantially the same as that shown in Fig. 1, except that the levers L^1 and L^2 are vertically disposed, and the fluid pressure motor comprising the cylinder C and the piston T is located directly beneath the track rail. This structure has the advantage of better mechanical characteristics than the structure shown in Fig. 1, but it has the disadvantage that pits are required beneath the track rail to accommodate the operating levers and the operating motors.

Referring now to Fig. 3, the apparatus shown in this view is the same as that shown in Fig. 1, except that the pivot pin B^2 , carrying the outside lever L^2 , is located below the pivot pin B^1 , and the cylinder C is vertically disposed. This modified structure has the advantage over that shown in Fig. 1, that the forces applied to the opposite sides of the car wheel are equal, and the further advantage that the reactions of the forces on pins B^1 and B^2 are in line, thus eliminating the unbalanced couple which would be exerted through the rail supports to the ties, resulting in secondary stresses.

It will, of course, be understood that in the case of each form of apparatus embodying my invention, each pair of braking bars is provided with a plurality of devices, similar to those shown in the drawings, disposed at intervals along the bars, substantially in accordance with the disclosure of the Bone application, referred to above.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. Railway braking apparatus comprising two levers pivoted below and at opposite sides respectively of a track rail and each having a first arm extending to the side of the rail opposite to that on which the lever is pivoted, two braking bars disposed on opposite sides of said rail and attached to said two lever arms respectively, and means for operating the other arms of said levers to move said bars toward and away from the rail.

2. Railway braking apparatus comprising two levers pivoted below and at opposite sides respectively of a track rail and each having an arm extending to the side of the

rail opposite to that on which the lever is pivoted, two braking bars disposed on opposite sides of said rail and attached to said two lever arms respectively, and a fluid pressure motor entirely supported by said levers for operating said braking bars and involving a cylinder connected with one lever and a piston operating therein connected with the other lever.

3. Railway braking apparatus comprising two levers pivoted below and at opposite sides respectively of a track rail and each having an arm extending to the side of the rail opposite to that on which the lever is pivoted, the pivotal point for one lever being below that for the other, two braking bars disposed on opposite sides of said rail and attached to said two lever arms respectively, and a fluid pressure motor supported entirely by said levers for operating said braking bars and involving a vertically disposed cylinder connected with one lever and a piston operating therein and connected with the other lever.

In testimony whereof I affix my signature.

HAROLD C. CLAUSEN.
